UNITED STATES PATENT OFFICE

ROBERT N. FALGE, OF DETROIT, MICHIGAN, ASSIGNOR TO GENERAL MOTORS RESEARCH CORPORATION, OF DETROIT, MICHIGAN, A CORPORATION OF DELAWARE.

LAMP-FOCUSING MECHANISM

Application filed April 30, 1928. Serial No. 274,077.

This invention relates to a device for adjusting the light bulb in an automobile headlamp so that it may be focused. My adjusting device is especially adapted for use with headlamps having a floating reflector and is so designed that the adjusting mechanism and the reflector may be removed as a unit from the lamp housing. It embodies a number of novel details of construction which will be pointed out in the course of the following description and covered in the appended claims. Among the novel features are the provision of a single spring to yieldingly hold the reflector in the housing, this spring also preferably serving to maintain the lamp bulb in adjusted position. The adjusting mechanism is also designed so that the bulb may be focused with the cover of the housing removed, and the adjustment will not be disturbed upon the subsequent application of the cover.

In the drawings:

Figure 1 is a vertical section through a headlamp in which my improved focusing device is embodied.

Figure 2 is a view showing the parts of the focusing mechanism.

Figure 3 is a view on line 3—3 of Figure 1.

10 indicates the lamp housing which may be of any desired shape and is provided at its forward end with a reduced portion 12 to receive the lamp cover, the reduced portion terminating in an inturned flange 14. 16 indicates the reflector which is mounted in the housing for axial sliding movement. The reflector is guided by studs 18 threaded in the flange 14 of the housing and slidably received in slots 20 formed in the outer edge of the reflector. The heads of the studs 40 limit the outward movement of the reflector. The lamp cover consists of a lens ring 22 equipped with lens 23 and adapted to be secured over the open end of the housing by means of a clamping ring 24. The clamping ring and the co-operating flange 12 on the casing are provided with inclined surfaces as shown so that the effect of tightening up the clamping ring by manipulation of the clamping bolt 26 is to force the 50 lens ring toward the housing and at the same

time through the lens 23 and gasket 28, applying pressure to the reflector urging it inwardly. This movement of the reflector is resisted by yielding means to be later described. This type of reflector mounting is referred to as floating since the reflector may adjust itself to the housing. The manner of securing the lens ring to the housing and the manner of mounting the reflector in the housing form no part of the present invention, except insofar as these elements cooperate with the parts later described.

30 indicates a guide secured to the reflector and within which the lamp socket 32 is slidably received. Within the socket is mounted the bulb 34 which is supplied with current through conductor 36. The guide 30 is notched as shown at 38 and the socket 32 is provided with a keyhole slot 40 registering with the notch. A U-shaped member 42 is equipped at one end with a T-head 44 adapted to pass through the notch and slot when aligned therewith and to be thereafter rotated through ninety degrees to the position shown in Figure 1 preventing separation of the parts. The T-headed portion 44 is provided with inclined surfaces 46 for engaging the edges of a notch and is also equipped with a spring 48 acting at one end against a plate 50 normally abutting against the top of the guide as shown in Figure 1. At the other end the spring 48 acts against disk 52 which bears against shoulders 54 provided on the member 42. The effect of the spring 48 is to yieldingly urge the member 42 upwardly and cause the inclined surfaces 46 to wedge in the slot 40 preventing accidental shifting of the lamp socket in its guide. The other end of the U-shaped member 42 is threaded to receive the adjusting bolt 56 which is slidably received in an aperture formed in the lamp housing. A coil spring 58 surrounds the bolt 56 and bears at one end against disk 60 slidably mounted on the bolt 56 and arranged to engage the housing as shown. At the other end the spring bears against the adjacent downturned end of the member 42. A stop is provided to prevent bodily inward movement of the screw 56, the stop taking the

form of an L-shaped member 62 secured at one end to the guide 30 and having the other end upturned to engage the end of the screw.

The construction operates as follows: The stop 62 prevents bodily inward movement of the adjusting screw 56 while the spring 58 yieldingly resists its bodily outward movement. Consequently the effect of rotation of the screw will be to cause the member 42 to travel in one direction or the other along the screw. Owing to its connection with the lamp socket 32 through the T-head 44 the socket will be drawn back and forth with it. By this means the lamp may be adjusted. The connection of the member 42 with a lamp socket through the T-head 44 and the keyhole slot constitutes, in effect, a universal joint, so that the parts 42 and 56 act purely as a means for adjusting the bulb forwardly and backwardly and cannot serve to distort the parts in case of inaccuracies in manufacture. For example, should the guide 30 and the aperture in the housing within which the adjusting screw is received be badly out of line, this will be taken care of by a rocking adjustment of the member 44 and the socket, without throwing the lamp out of focus as would be the case were the connection a rigid one.

The spring 58 performs the additional function of yieldingly urging the reflector 16 outwardly of the housing. The spring pressure is applied to the reflector through the screw 56, stop 62 and the sleeve 30.

It has been found best to adjust the reflector with the lens removed. When this is done the spring 58 forces the reflector to its outermost position where it engages the heads of the studs 18. This movement of the reflector carries the whole focussing mechanism with it, including the member 42 and the screw 56. However, the adjustment of the bulb with respect to the reflector is not altered by the removal of the cover nor conversely is it affected by the subsequent application of the cover. This is of considerable advantage as it enables focussing to be done under the most desirable conditions and yet assures that the adjustment will not be disturbed upon re-assembling the cover.

It is also of considerable advantage in assembling the headlamps to have all of the parts of the focussing mechanism carried by the reflector. This sub-assembly may then be slipped into the lamp housing, the cover applied, and the lamp is then ready for use.

I claim:

1. A lamp including a housing, a reflector mounted in the housing for axial sliding movement, means for limiting the forward movement of the reflector, a lamp socket slidably mounted in the reflector, adjusting means for the socket comprising a screw slid-

ably mounted in the housing, means secured to the reflector for positively preventing bodily movement of the screw in one direction, means having threaded engagement with the screw and universally connected to the socket for adjusting the latter back and forth upon rotation of the screw, and spring means engaging said last named means and the housing for urging the reflector outwardly and maintaining said adjusting means in adjusted position. 70 75

2. The combination as defined in claim 1, said spring means comprising a coiled spring encircling the screw.

3. A headlamp including a housing, a reflector slidably mounted in the housing, means for limiting the forward movement of the reflector, a lamp socket, a guide secured in the reflector, and slidably receiving the socket, a socket adjusting member having at one end universal connection with the socket to allow for misalignment of parts, an adjusting screw slidably mounted in the housing and having one end exposed at the rear thereof for manipulation, said screw having threaded engagement with the adjusting member, said guide being provided with a fixed abutment arranged to engage the screw and positively limit its forward movement, and a spring encircling the screw between the housing and the adjusting member and reacting at one end against the housing and at the other end against the socket adjusting member to hold the member in adjusted position on the screw and yieldingly urge the reflector away from the housing. 90 95

4. A lamp including a housing, a reflector slidably mounted in the housing, a lamp socket, a guide secured in the reflector and slidably receiving the socket, a socket adjusting member having universal connection with the socket to allow for misalignment of parts, an adjusting screw slidably mounted in the housing and having threaded engagement with the adjusting member, said guide being provided with a fixed abutment adapted to engage the inner end of the screw, and a coil spring encircling the screw between the housing and the adjusting member and reacting at one end against the housing and at the other end against the socket adjusting member to hold the member in adjusted position on the screw and to yieldingly urge the reflector away from the casing. 105 110 115 120

In testimony whereof I affix my signature.

ROBERT N. FALGE.
